United States Patent Office

Des. 232,414
Patented Aug. 20, 1974

232,414

TRAVEL IRON

William J. Rakocy, Clifton, N.J., assignor to North American Philips Corporation, New York, N.Y.

Filed Jan. 24, 1972, Ser. No. 220,548

Term of patent 14 years

Int. Cl. D7—05

U.S. Cl. D7—202

FIG. 3

FIG. 2

FIG. 1

FIG. 4

FIG. 5

FIG. 1 is a front elevation view of my new design for a travel iron;

FIG. 2 is an end elevation view thereof;

FIG. 3 is a top plan view thereof;

FIG. 4 is an end elevation view thereof, opposite the FIG. 2 end; and

FIG. 5 is a bottom plan view thereof.

I claim:

The ornamental design for a travel iron, as shown.
